UNITED STATES PATENT OFFICE

141,686

DESIGN FOR A SEED MEASURING DEVICE

James B. Hagle, South Bend, Ind.

Application October 17, 1944, Serial No. 115,833

Term of patent 14 years

(Cl. D52—1)

To all whom it may concern:

Be it known that I, James B. Hagle, a citizen of the United States of America, residing at South Bend, county of St. Joseph, and State of Indiana, have invented a new, original, and ornamental Design for a Seed Measuring Device, of which the following is a specification, reference being had to the accompanying drawing, forming a part thereof, wherein:

Figure 1 is a side elevation of a seed measuring device, showing my new design.

Figure 2 is a top plan view.

Figure 3 is a bottom plan view.

I claim:

The ornamental design for a seed measuring device, as shown.

JAMES B. HAGLE.
